CLAIM

I claim the ornamental design for a housing for an electric hair clipper, as shown and described.

DESCRIPTION

FIG. 1 is a perspective view of a housing for an electric hair clipper, depicting an embodiment of the present invention; FIG. 2 is the rear view of the housing of FIG. 1; FIG. 3 is the front view of the housing of FIG. 1; FIG. 4 is the left side view of the housing of FIG. 1; FIG. 5 is the right side view of the housing of FIG. 1; FIG. 6 is the top view of the housing of FIG. 1; and, FIG. 7 is the bottom view of the housing of FIG. 1. The broken lines illustrate a portion of housing and form no part of the claimed design.

1 Claim, 4 Drawing Sheets
